LIGHTING UNIT

Frederic C. Winkler, Lakewood, Ohio, assignor to Westinghouse Electric & Manufacturing Company, East Pittsburgh, Pa., a corporation of Pennsylvania

Application November 12, 1937, Serial No. 174,196

5 Claims. (Cl. 240—78)

My invention relates, generally to lighting units, and, more particularly to interior lighting units of the suspension indirect type.

The object of the invention, generally stated, is to provide an indirect lighting unit which shall be of simple and light weight construction and which may be easily and economically manufactured.

A more specific object of my invention is to provide a reflector basin for an indirect lighting unit having supporting ears or members integrally formed on the inside thereof.

A further object of the invention is to provide a basin or bowl for an indirect lighting unit which may be constructed of two separately formed portions suitably joined together into a unitary structure in such manner that entire outside surface is not marred by screws, rivets or the like.

Another object of the invention is to provide a lighting unit of the hanging or suspension type wherein the hanger may be economically and readily shortened to accommodate ceilings or mounting surfaces of different heights.

These and other objects will become apparent from a study of the following detailed description taken in conjunction with the drawing in which:

Figure 1 is a partially sectionalized view in elevation of a lighting unit embodying the principal features of the invention.

Fig. 2 is a view showing details of the hanger construction, and

Fig. 3 is an enlarged view of a portion of the basin of Fig. 1.

Referring now to the drawing, which illustrates a preferred embodiment of the invention, the reference character 10 designates the hanger of the fixture and reference character 11 the basin or reflector.

40 The hanger comprises a ceiling canopy 12, stem 13, socket 14 and husk 15. In this instance, the socket 14 for the lamp 16 is attached to the stem 13 by means of a socket cap 17 which is secured to the top of the socket by means of screws 18.

45 In order to provide for shortening the hanger to accommodate varying installation conditions the socket cap 17 is secured to the end of the hanger by means of a removable pin 19 extending through suitable aligned openings in the stem and cap. The husk, which is loosely mounted to

50 slide up and down the stem is curved inwardly at the top so that it rests upon the outside edge 21 of the socket cap, as shown in Fig. 2, and at the same time serves as a retainer for the pin 19

which is of such length that it cannot slip out of position when the husk is in its down position.

With this construction, the hanger stem may be shortened by lifting the husk until the pin can be removed, the stem shortened to the desired length and a new hole drilled through the end thereof to receive the pin 19. Heretofore, it has been the practice to attach the socket cap to the stem by means of threads which required that new threads be cut whenever it was desired to shorten the hanger.

In order to provide a basin 11 of light weight construction, of good appearance, and which will produce efficient, glare free and well distributed illumination, it is preferably constructed of sheet aluminum and is given a finishing treatment by the Alzak process for permanence and simplified cleaning.

Since it is highly desirable in the manufacture of basins of this type to obtain as near perfect an outside finish and appearance as possible, provision must be made for supporting the basin from the hanger in such manner that the outside surface of the basin is not marred or disfigured in any way by attaching lugs or other supporting means to the inside surface thereof.

For this reason and also to obtain economy in manufacture, the basin 11 is preferably constructed in two parts which are suitably fastened together to form a unitary member. By means of 30 this construction, it is possible to form the supporting lugs for the basin integral with one of the other of its two parts thereby making it unnecessary to fasten these lugs to the inside of the basin by riveting or welding or to do anything which 35 will mar or otherwise disfigure the outside surface or interfere in any way with the finishing treatment of the basin.

In this instance the basin 11 comprises a top part 22, which is in the form of a one-piece shallow bowl with a central bottom opening of relatively small diameter as compared to the large top opening. The bottom part 23 of the basin is likewise formed in one piece and is bulb shaped, as shown, to generally conform to the shape of 45 the lamp bulb. The parts 22 and 23 may be formed from sheet material by a spinning or other suitable process.

The upper part 22 of the basin is so formed as to provide a channel 25 about the central opening 50 and spaced integral supporting lugs 26 which are pierced to receive the hook-shaped ends 27 of the supporting rods 24, as shown in detail in Fig. 3.

The channel 25 thus formed is utilized in this 55

- instance to attach the bottom part 23 of the basin to the top part 22 which may be accomplished by crimping, swedging or spinning the two parts together in mechanically interlocked relation. It will be apparent that this arrangement permits the basin to be constructed without resorting to riveting or welding and provides a seam or joint which, when finished, is almost imperceptible. In other words, there are no screws or rivet heads to show and the character of the basis material is not changed in any way to interfere with the surface finishing process such as would result if the two parts were welded together or the lugs 26 welded to the inside surface of the basin.
- 15 In view of the foregoing, it will be apparent that by utilizing this construction, a basin may be produced in the most economical manner having all the advantages as to appearance and performance as a one-piece construction. In addition, this construction permits the production of an aluminum basin with inside or concealed supporting lugs without a marred or otherwise disfigured outside surface when finished.
- 20 Although I have described a specific embodiment of my invention, it will be obvious to those skilled in the art, that various changes may be made in the details of construction, such as in the proportion and design of the several cooperating parts, without departing from the spirit of the invention, as defined by the appended claims.
- 25 I claim as my invention:
1. An indirect lighting unit comprising a hanger provided with a socket for supporting the lamp and a husk element covering the socket, a bowl-shaped metallic reflector adapted to be supported beneath the lamp, said reflector being constructed of a top portion having a central bottom opening defined by an external channel portion with upturned ear portions on the inside and a separate cup-shaped bottom portion having its upper edge mechanically locked about the channel portion, and means interposed between the ear portions of the top portion of the reflector and the husk element for supporting the reflector.
  - 30 40 45 2. In an indirect lighting fixture comprising a hanger provided with a socket for supporting the lamp and a husk element covering the socket, a bowl-shaped metallic reflector comprising a relatively large and shallow top portion having a

central bottom opening defined by an integrally formed downwardly extending channel portion, a separate bulb-shaped lower portion having an outwardly extending flange portion with the edge thereof crimped about the channel portion, said top portion of the reflector having upwardly extending support-ears integral with the channel portion, and means interposed between the husk element and the integral support-ears for supporting the reflector beneath the lamp.

3. In an indirect lighting fixture comprising a hanger provided with a socket for supporting the lamp and a husk element covering the socket, a bowl shaped metallic reflector comprising a shallow bowl-shaped top portion having a central bottom opening with an external inturned channel-shaped flange portion integral therewith and extending downwardly below the bottom of the top portion and a separate bulb-shaped lower portion having an outwardly extending flange at its upper edge portion mechanically formed in fixed relation about the channel-shaped flange portion of the upper portion, and support means interposed between the external husk and the in-turned flange portion of the top portion for supporting the reflector beneath the lamp.

4. An indirect reflector basin for a lighting fixture comprising a shallow bowl-shaped metallic top member having a central opening provided with an integrally formed downwardly extending channel portion, and a separate bulb-shaped metallic lower member having an outer transversely extending flange portion at its upper edge portion mechanically interlocked about the outside surface of the channel portion of the top member to form a unitary basin structure.

5. A reflector basin for an indirect lighting unit comprising a shallow bowl-shaped top member of opaque material having a central bottom opening provided with an integrally formed downwardly extending external channel portion and inturned ear portions integral therewith, said inturned ear portions being adapted to support the basin, and a separate lower bulb-shaped member of opaque material having an outwardly extending flange at its upper edge bent about the outside of the channel portion of the top member to provide a unitary basin construction.

FREDERIC C. WINKLER.
